UNITED STATES PATENT OFFICE.

JOSEPH DRZEWIECKI, OF DETROIT, MICHIGAN.

DOOR-LATCH.

1,184,084.

Specification of Letters Patent. Patented May 23, 1916.

Application filed September 30, 1915. Serial No. 53,284.

To all whom it may concern:

Be it known that I, JOSEPH DRZEWIECKI, a subject of the Czar of Russia, residing at Detroit, in the county of Wayne and State of Michigan, have invented certain new and useful Improvements in Door - Latches, of which the following is a specification, reference being had therein to the accompanying drawings.

10 This invention relates to door latches especially designed for automobile doors, and the primary object of my invention is to provide a simple, durable and inexpensive latch which may be concealed in a door frame or door with the actuating mechanism thereof in proximity to the upper edge of the door, whereby it may be easily manipulated to release the door, the actuating mechanism visible being in the form of a button which 15 presents a neat appearance in connection with an automobile door and obviates the necessity of using exposed protruding handles or cranks as is the common practice.

A further object of my invention is to provide a door latch which automatically secures a door, when closed, the principal part 25 of the latch being in the form of a semi-cylindrical shell disposed whereby an edge thereof rides into engagement with a keeper 30 and another edge engages a frame or body projection, thus holding the door until the keeper is shifted to allow the shell to move away from the projection.

The mechanical construction by which I 35 attain the above and other objects will be hereinafter specifically described and then claimed, and reference will now be had to the drawing, wherein—

Figure 1 is a perspective view of a portion 40 of a door frame provided with a latch in accordance with my invention; Fig. 2 is an enlarged perspective view of a detached latch; Fig. 3 is a horizontal sectional view of a portion of a door frame showing a 45 portion of the operating mechanism of the latch keeper in plan; Fig. 4 is a similar view illustrating a modified form of the operating mechanism of a latch keeper, and Fig. 5 is a similar view showing a door in 50 a closed position relative to a portion of an automobile body.

In the drawing, 1 denotes a portion of an automobile body having a doorway 2 adapted to be closed by a door 3.

55 4 denotes a plate secured in the doorway

2 and on the side of the automobile body 1, said plate having a projection 5 with an edge thereof beveled, as at 6.

7 denotes a recess in the door body or frame 3 and closing said recess is an angle 60 strike plate 8 provided with communicating openings 9 and 10, said openings providing clearance for the projection 5 when the door 3 is swung to a closed position.

11 and 12 denote horizontally disposed 65 corner plates secured to the inner side of the angle strike plate 8, at the upper and lower ends of the openings 9 and 10. These corner plates may be secured to the angle strike plate by spot brazing or in any suitable manner.

13 denotes a vertically disposed pivot pin journaled in the corner plates 11 and 12. Mounted on the pivot pin 13 is a vertically disposed yoke 14 and the ends of said yoke 75 are connected by a semi-cylindrical shell 15, which has the longitudinal edges 16 and 17 thereof equi-distant relative to the yoke 14, as best shown in Fig. 5.

18 denotes a coiled spring encircling the 80 lower end of the pivot pin 13, between the corner plate 12 and the lower end of the yoke 14, said spring having one end thereof bearing against the angle strike plate 8 and the opposite end thereof connected to the 85 yoke, as at 19. This spring is adapted to maintain the yoke 14 normally protruding into the opening 10 of the angle strike plate, whereby it will impinge the projection 5, when the door is closed, and partially rotate the pivot pin 13 to place the edge 17 of the shell 15 in engagement with the projection 5.

20 denotes a keeper rod journaled in the corner plate 11 and extending upwardly through a groove 21 in the inner side of the door frame or body 3, as best shown in Fig. 1. The lower end of the keeper rod 20 has a hook shaped keeper 22, adapted to engage the edge 16 of the shell 15 and hold said shell in engagement with the projection 5 of the automobile body, thereby preventing the door 3 from being opened until the keeper rod 20 is rocked. The upper end of the keeper rod 20 extends into a recess 23 100 at the upper edge of the door frame or body 3, said keeper rod terminating in a crank 24 having a button 25 protruding from an escutcheon plate 26 closing the recess 23. Within the recess 23 is a com- 105

pression spring 27 engaging the crank 24 to hold the keeper 22 in engagement with the shell 15.

When closing the door, the yoke 14 encounters the projection 5, as heretofore stated, turning the shell 15 until the keeper 22 engages the edge 16 of said shell, then the door is held in a closed position, until the button 25 is pressed to swing the keeper 22 to one side and allow the spring 18 to restore the shell 15 to normal position.

The beveled edge or end 16 of the projection 5 provides clearance for the edge 17 of the shell 15 as said shell swings in position to latch the door, and the outer wall of the shell 15 holds the keeper 22 in a retracted position until the edge 16 of said shell is in position to be engaged by the keeper.

As shown in Fig. 4, the keeper rod 20 has an additional crank 24^a provided with a button 25^a protruding from that side of the door opposite the button 25, consequently the keeper can be shifted from the outer or inner side of an automobile, particularly a limousine.

It is thought that the utility of my improved door latch will be apparent without further description, and while in the drawing there is illustrated a preferred embodiment of my invention, it is to be understood that the structural elements are susceptible to such variations and modifications as fall within the scope of the appended claims.

What I claim is:—

1. A door latch comprising a projection adapted for attachment to an automobile body in the doorway thereof, an angle strike plate adapted for attachment to a door and provided with openings, a pivoted yoke supported by said strike plate and adapted to impinge said projection, a shell carried by said yoke in the openings of said angle strike plate and adapted to engage said projection and hold the door closed, and a keeper adapted for operation at the upper edge of the door to engage said shell and maintain said shell in engagement with said projection.

2. A door latch comprising a stationary projection, an angle strike plate adapted for attachment to a door, a pivoted yoke supported from said strike plate and adapted to impinge said projection, a shell carried by said yoke and adapted to engage said projection, a keeper adapted to engage said shell and maintain said shell in engagement with said projection, and means connected to said yoke adapted to move said shell out of engagement with said projection when said shell is released by said keeper.

In testimony whereof I affix my signature in presence of two witnesses.

JOSEPH DRZEWIECKI.
